UNITED STATES PATENT OFFICE.

CLARENCE P. HOLLISTER, OF NEW YORK, N. Y.

DESIGN FOR A COOLING-RADIATOR FOR AUTOMOBILES.

48,180.

Specification for Design.

Patented Nov. 23, 1915.

Application filed September 14, 1915. Serial No. 50,716. Term of patent 3½ years.

To all whom it may concern:

Be it known that I, CLARENCE P. HOLLISTER, a citizen of the United States, residing at New York city, in the county of New York and State of New York, have invented a new, original, and ornamental Design for Cooling - Radiators for Automobiles, of which the following is a specification, reference being had to the accompanying drawing, forming part thereof.

Figure 1 is a front elevation of a cooling radiator for automobiles, showing my new

design. Fig. 2 is a side elevation of a cooling radiator for automobiles, showing my new design. Fig. 3 is a plan view of a cooling radiator for automobiles, showing my new design.

I claim:

The ornamental design for a cooling radiator for automobiles, as shown.

CLARENCE P. HOLLISTER.

Witnesses:

HARRY H. STERNBERG,

CARL W. BLISS.
